UNITED STATES PATENT OFFICE.

ROSS HUNTER, OF MILWAUKEE, WISCONSIN.

TRAY-LIFTING DEVICE.

Specification of Letters Patent.

Patented Apr. 8, 1919.

1,299,475.

Application filed October 15, 1917. Serial No. 196,607.

To all whom it may concern:

Be it known that I, Ross HUNTER, a citizen of the United States, residing at Milwaukee, in the county of Milwaukee and State of Wisconsin, have invented certain new and useful Improvements in Tray-Lifting Devices, of which the following is a specification.

My invention refers to tray lifting devices and particularly to trunks or packing cases containing such devices which devices comprise a plurality of trays mounted on lazy tongs so that the whole may be extended or nested within the trunk or case for access thereto or packing thereof, the whole being arranged so as to be easily operable by moving the lazy tongs.

I am aware that it has heretofore been proposed to construct salesmen's trunks and the like wherein are employed a series of trays carried by lazy tongs. Among the objections to such previously proposed arrangements may be mentioned the manner of locking the lazy tongs in extended position; the fact that special connections between the lazy tongs and trays have to be provided, and the method of operating is far from satisfactory.

One of the objects of my invention is to provide a novel and simple locking device for holding a series of nesting trays in extended position.

Another object is to provide a locking arrangement which can be effected by movement of the tray supports.

A further object is to provide a tray lifting device composed of a minimum number of parts and one that can be operated with the least possible effort.

A further object is to provide a set of braced lazy tongs adapted to support trays or the like on the braces doing away with special connections between the trays and the tongs.

A still further object of my invention is to provide a lazy tong arrangement which will permit extending several trays, and a novel locking arrangement whereby the opening movement will effectively lock the lazy tongs in extended position, and the clos-

ing movement will unlock the tongs to permit closing thereof.

Another object is to provide a tray lifting device for cases of the class described wherein a novel locking arrangement is provided. 55

A further object is to provide an improved packing box or trunk which will be simple in construction, convenient in use and efficient in operation.

These and other objects will be apparent 60 from the drawings, wherein—

Figure 1 is a perspective of a packing case embodying my invention, the trays being shown in extended position.

Fig. 2 is an end elevation of the trays extended, the case being shown in section.

Fig. 3 is a vertical section of the case showing the trays in retracted or compact position and the case closed, and

Fig. 4 is a top plan view of the top tray. 70

In the drawings, 5 represents a case or trunk of any well known construction provided preferably with casters 6 and the usual type of flat lid 7. Mounted within the case 5 are, in the embodiment shown, three trays 8, 9 and 10 supported on lazy tongs one at each end of the case 5. The lazy tongs as far as the extensible motion is concerned are of usual construction comprising crossed members 12, 13, pivotally connected at 14, 80 the length of the members 12 and 13 being such as to enter the case 5 when in retracted position as shown in Fig. 3. The lowermost pair of members forming the lazy tongs are designated as 12^a and 13^a pivotally connected 85 at 14^a. Heretofore, the method of mounting the trays 8, 9 and 10 on the lazy tongs has been to provide slots in the ends of the trays with which registering members on the lazy tongs coöperate, or the provision of some other sliding connection between the lazy tongs and the trays themselves, thus necessitating in every instance special trays and special forms of connection. Such a construction makes removal and replacement of 90 the trays rather difficult. To overcome these objections I have formed a tray lifting device comprising lazy tongs and at the ends of the members 12 and 13 provided braces 15, best seen in Fig. 1 extending from the 100

ends of the members 12 and 13 to the similarly disposed ends of the lazy tongs at the other end of the case, thus forming a rack having horizontally disposed braces. The 5 lifting device therefore forms a compact substantially rigid structure in itself. I prefer to secure the lower end of the cross members 12^a to the inner portion of the case 5 making a pivotal connection 12^b therebetween but preventing bodily movement thereof. This connection may be made in any desired manner such as, for instance, by bolts extending through the lower ends of the members 12^a and the adjacent ends of 10 the case. The lower ends of the members 13^a are free as it is, of course, well known that when the lazy tongs are extended the distances between the ends of the members are changed. This fact I use as the basis 15 for my novel locking or holding arrangement.

Mounted on the cross braces 15 connecting the similarly disposed ends of the cross members forming the lazy tongs are the 20 trays 8, 9 and 10. These are provided at their forward under edges with cleats 16 engaging the braces 15 at the forward portions of the lazy tongs. Provision of these cleats fixes the relative movement of the 25 trays with respect to the front braces 15, thus permitting sliding movement of the rear braces 15 with the several trays mounted thereon without displacing the trays. In Fig. 1, I have shown mounted on the second 30 set of braces two trays 9 and 9^a as the novel lazy tong arrangement of my invention permits the use of more than one tray if desired without having to re-arrange the tray lifting structure. It will be observed that the 35 compensation is between the trays and the braces and not by virtue of any special connections between the trays and the lazy tongs.

As handles to operate the lifting arrangement, I prefer to provide flexible member 17 attached preferably to the front braces 15 and extending through slots 18 in the bottom of the top tray 8, the slots being positioned near the ends of the tray, thereby applying the lifting forces to the tray supports 40 and not to the trays.

On the bottom of the case 5 near the rear wall thereof and at each end I fasten cleats or stops 20 in any suitable manner such as 45 by screws, the ends of the cleats which engage the legs 13^a being cut under and the ends of the legs 13^a being shaped to engage said cut under portion when brought into engagement therewith, thus making a dove-tailed locking connection. The position of 50 the cleats 20 is such that the lower free ends of the members 13^a will bear thereagainst when the lifting device is fully extended and

will form a holding or locking means for the lazy tongs.

The operation of the device is as follows: The parts being nested within the trunk or case 5 as shown in Fig. 3, the top 7 is opened and the flexible handles 17 are grasped. An upward pull on the handles 70 will extend the tongs and raise the trays. When the tongs have been extended to substantially fully extended position as determined by the abutment 21, that is when the ends of the legs 13^a ride over the stops 20, 75 then a slight rearward movement brings the lower free ends of the members 13^a into firm engagement with the cleats 20, thus securely locking the tray lifting device in extended position. The parts then will be in the position as shown in Figs. 1 and 2. It will be observed that access to all of the trays may be readily had and because of the fact that the trays merely rest on the braces and are not connected thereto, any one or all may be 80 removed and other trays or the same trays replaced. When it is desired to collapse the trays the operator moves the upper tray outwardly, that is, toward himself, thus causing the lower free end of the member 13^a 85 to ride over the cleat 20 and then lowers the trays into the position shown in Fig. 3.

By varying the weight and construction of the various parts it will be readily seen that the novel tray lifting device of my invention may be adapted to support any sort of merchandise. I prefer to utilize the present arrangement for holding apparel which is easily crushed when packed in a trunk or box such as shirt waists and the like and 90 therefore the construction which I prefer to employ is light in nature. However, as before stated, merchandise or goods of any character may be displayed or carried or stored by making the lazy tongs and trays 95 sufficiently strong to sustain the weight of the particular goods therein packed. When utilized as a shirt waist box, the top 7 may be covered with suitable material to form an 100 article of utility such as a settee, or the casing may be finished in different kinds of 105 woods or steel to represent any desired article of furniture.

I am aware that modifications of such a device are possible and such modifications of 110 which this structure is susceptible I consider as coming within the spirit of my invention.

I claim:

The combination with a trunk comprising 115 a body portion and a vertically swinging cover, of a plurality of trays fitting within said body portion, sets of lazy tongs supported within the trunk at the opposite sides of the trays, the front lower ends of the sets 120 of tongs being pivotally supported adjacent

the front and the bottom of the trunk, means secured within the trunk against which the rear lower ends of the sets of lazy tongs engage to hold the tongs in upwardly extended position, a pair of rods connecting corresponding members of the sets of tongs upon which is supported a tray, and means for detachably supporting the front of the tray by

and without sliding movement relative to the front supporting rods and permitting the tray to slide relative to the rear supporting rod during the raising and lowering of the trays.

Signed at Chicago, State of Illinois, this 13th day of October, A. D. 1917.

ROSS HUNTER.
